CLAIM

The ornamental design for a spring clip, as shown and described.

DESCRIPTION

FIG. 1 is a front view of a spring clip showing my new design, the rear view being a mirror image thereof;

FIG. 2 is a side view of the spring clip of FIG. 1, the opposite side view being a mirror image thereof;

FIG. 3 is a top plan view of the spring clip of FIG. 1;

FIG. 4 is a bottom plan view of the spring clip of FIG. 1; and,

FIG. 5 is a frontal perspective view of the spring clip of FIG. 1 viewed from an acute angle to the right thereof.
